(57) **CLAIM**

The ornamental design for a solar cell, as shown and described.

DESCRIPTION

FIG. 1 is a top perspective view of the first embodiment of a solar cell showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a back elevation view thereof;

FIG. 7 is a front elevation view thereof;

FIG. 8 is a top perspective view of the second embodiment of a solar cell showing our new design;

FIG. 9 is a top plan view thereof;

FIG. 10 is a bottom plan view thereof;

FIG. 11 is a right side elevation view thereof;

FIG. 12 is a left side elevation view thereof;

FIG. 13 is a back elevation view thereof; and,

FIG. 14 is a front elevation view thereof.

The broken lines shown in the drawing views are included for the purpose of illustrating unclaimed portions of the solar cell that form no part of the claimed design. All elements shown in the FIGS. 1-3, and 8-10 are structural lines on the surface and are flat with the top surface.
